UNITED STATES PATENT OFFICE.

ORVILLE U. DESHA, OF FORT COLLINS, COLORADO.

KEY ACTION FOR TYPEWRITERS AND OTHER MACHINES.

Application filed March 24, 1927. Serial No. 178,084.

My invention relates to improvement in key-action for typewriters and other type bar and key operating machines, actuating means at all times operatively connecting the 5 type bar and key lever moving the type bar to printing point upon the depression of the key lever and means reversely breaking the said connection after the printing impact of the type bar for the return of the type bar 10 to normal position while the key lever is in depressed position, this broad object being the subject matter of an application filed by me on November 5th, 1923, Serial No. 672,871, upon which Patent 1,643,203, issued Sept. 20, 15 1927, as a contradistinction between previous devices comprising a detachable connection or gap at some point between the key lever and type bar after the latter has been given the movement necessary to effect the printing 20 and before the key lever has completed its movement.

The specific object of the present invention is to provide improved means of the character specified above whereby the reversely breaking actuating connection between the key lever and the type bar is in the nature of a 25 novel operative structure that may readily be incorporated in certain typewriting machines with only slight modifications of the 30 structural features of said machines as they now exist.

I have shown my invention embodied, in the present instance, in a typewriter similar to the L. C. Smith standard machine, and in 35 which the invention may be readily incorporated by slight modification of the structural features of the machine in effecting such incorporation. It should be understood, however, that the invention is not restricted to 40 use in a machine of this type but may be employed wherever found available.

The desired principle of operation, new 45 mechanical functions, operative expedients, and other objects and advantages will herein- 50 after be described in the following disclosure and will be more particularly pointed out in the appending claims. In the accompanying drawing wherein like reference characters indicate corresponding parts in the various

In the drawing Figure I, is a vertical section of a typewriter, one key action only 55 being shown in normal position; Fig. II, represents a view of the key mechanism similar to Fig. I, the key lever being shown depressed and responding the type bar. Fig.

III, also key mechanism similar to Fig. I, the key lever being shown in a depressed position and the type bar returned to its initial position. Fig. IV is a skeleton view of the key 60 mechanism for illustrative purposes in describing the mode of operation of the machine shown. It is understood, of course, that for the sake of clearness and to avoid complication of drawings the applicant has omitted to show the remainder of the key levers and type bars as well as other devices necessary or advisable in the complete machine. 65

In the embodiment in Fig. I, 1 indicates the frame of a typewriter, 1^a indicates the 70 front and 1^b the rear, having a common power driven paper carriage 2 supported in the rear on guide rod 3 and in front on guide 4; 5 indicates the common platen carried by the paper carriage 2. 6 indicates one of the 75 usual type bars carrying the type 7 at its front end, and is arranged to turn on pivot 9 in the form of a segment disposed vertically below the frame face of the plate 10 thereby providing the type 7 with a common printing point A as the type bar 6 turns on pivot 9 from normal horizontal position of rest on the segment 11 in the usual manner.

12 indicates one of the key levers carrying 80 at the front end finger key 13, the rear end pivoted at 14 to bar 14^a in the rear of the machine, and is kept normally in its elevated position by the spring 15 supported by bar 15^a at normal rest of key lever bearing 85 against the under-side of stop bar 15^b above the key lever 12. Key lever 12 is formed with downward offset or broken angles 16 and 16^a arranged to provide room for bar 20, and key lever is also provided with upwardly 90 projecting arm 16^b behind the bar 20, and 95 provides a saddle-backed seat 17 for the coupling hereinafter described.

The key lever 12 is described as having two 100 incidents of operation, namely; the incident of depression and the incident of release. The incident of depression is disclosed by the movement of key lever 12 from radius B to radius C, and the incident of release is disclosed by the movement of the key lever 12 back from radius C to radius B. The type 105 bar 6 is described as having two incidents of operation, namely; incident of response and the incident of recoil. The incident of response of the type bar 6 is disclosed by the movement of the type bar from its initial 110 rest radius E to the printing point A, indicated by radius F, forming arc G from pivot

9. The incident of recoil of type bar 6 is disclosed by its movement from the printing point A back to normal rest E. These incidents of operation are, of course, present 5 in type bars of nonreversely breaking action in so far as the incident of response, E to A, of the type bar 6 already known to the art occurs simultaneously with the incident of depression, B to C, of key lever 12, and the 10 incident of recoil A to E of the type bar occurs simultaneously with the incident of release, C to B, of the key lever, but the novelty of my invention relative to the correlation of incidents of operation of the key lever with 15 that of the type bar in providing the operative expedient by which both the incident of response, E to A, of the type bar and the incident of recoil, A to E, occur during the one incident of depression, B to C, of the key 20 lever. This operative expedient is accomplished, in this case, by a novel reversely breaking actuating coupling being the principal subject matter of this application, engaging the parts connecting the key lever 25 with the type bar, hereinafter described.

18 indicates one of a series of angular vibratory levers, with rear angle vertex 18^a and front vertex 18^b the part between said angles being horizontal; part below vertex 30 18^a being perpendicular to key lever; part above vertex 18^b slanting backwards, the vibratory levers correspond in number with the type bars 6 and key levers 12. Lower ends of 35 vibratory levers 18 are pivoted at 19 in a bar 20 above the key lever 12 and extending across the machine; upper end of the vibratory lever is pivoted at 21 to a backward pull-rod 21^a.

22 is a backward draw link and 23 is a backward thrust link of what is hereinafter 40 described as a reversely breaking actuating coupling which connects the key lever and vibratory lever.

Intermediately their ends each of the backward draw link 22 is pivoted at 25 near the 45 front vertex 18^b of the angular vibratory lever 18, and the rear end of the backward draw link 22 is pivoted at 24 to the rear end of the backward thrust link 23, the front end of the backward thrust link 23 being pivoted 50 at 26 to the upwardly projecting arm 16 of key lever 12 behind bar 20 and pivot rod 19 of angular vibratory lever 18.

The relative normal position of pivots 24, 55 25 and 26 are engaged in a line J J Fig. IV, substantially slanting forward and upward from pivot 24 to pivot 25.

It will be observed that the backward draw link 22 and thrust link 23 constituting the 60 reversely breaking actuating coupling operate in a plane above the key lever. Also it will be noted that the backward draw link 22 operates, in the rear of pivot 19 and cross bar 20 which discloses this link to be rearwardly disposed.

65 27 is a return spring engaging one of the

plurality of holes 27^a in the front end of the backward draw link 22 and the other end engaging hole 27^b in the depending edge of cross bar 27^c in the front of the machine which spring serves to hold link 22 in tension 70 lock and to vibrate lever 18 forward to normal position shown in Fig. I, and to return it and the type bar 6 to normal position E after operation.

28 is a rearwardly extended nose of draw 75 link 22 and is designated as a fulcrum trip, pivot 24 being the fulcrum point about which draw link 22 turns in cooperating with top of key lever 12 in lifting thrust link 23 out of seat 17. Draw link 22 cooperates with return bar 29 in restoring the reversely breaking actuating coupling to normal operative position during the incident of release of the key lever. For additional means for restoring said coupling to normal operative position angle point 16^a of key lever 12 is provided with a noise-absorbing contact-point 16^b communicating with the under edge 22^a of the front end of draw link 22.

While draw links 22 and thrust links 23 80 are operating under tension lock, spring 27 is drawn to high tension, and then at this stage the energy is diverted to the recoil of the type bar as thrust link 23 is tripped out of tension lock, thereby attaining the operative expedient by which energy stored in responding the type bar is diverted to its recoil.

The new mechanical movements and operation thereof are important factors of the invention in providing the novelty function of the key action. A further description of the operative principle, therefore, follows: The 90 geometrical circle H H, Fig. IV, with a diametrical line J J from the backward border pivots 24 to forward border pivot 25 circumscribes what is termed the actuating plane. The diametrical line J J from the backward border pivot 24 to the forward border pivot 100 25, indicates the divert tension line and divides the actuating plane into the upper zone of response K and a lower zone of reaction L; the zone of response K having to do with the response of the type bar 6 from radius E to radius F while the key lever 12 is being depressed from radius B to radius D; and the lower zone of reaction L having to do with the recoil of the type bar 6 from the printing point A to radius E at rest while the key lever 12 is being continually depressed from 110 radius D to radius C of depression. The normal or idle position of backward thrust link 23 operates in the upper zone of response K as shown in Figs. I, II and IV. It is necessary that the backward draw links 22 be of such length between pivots 24 and 25 and be in such form and so engaged in such fashion as to permit the pivotal point 26 to oscillate 115 between pivots 24 and 25 in crossing and re-crossing the divert tension line J J. The 120

125 130

backward draw link 22, therefore, is angular formed and is also designated as the long link of the reversely breaking actuating coupling. The backward thrust link 23 is relatively short. In this case, the elements 22 and 23 of the reversely breaking actuating coupling are folded during the incident of depression from radius B to radius D of the key lever 12 and simultaneously with the incident of response 10 of type bar 6 from radius E to printing point A; and the foldment of elements 22 and 23 unfolding during the remainder of depression, radius D to radius C of key lever 12 simultaneously with the recoil of the type bar 15 from printing point A back to radius E, the type bar recoiling to cushion 11 at substantially the same instant the key lever contacts with stop bar 15°.

Saddle-backed seat 17 provided by the key lever 12 stops pivotal point 24 and effects responsive tension lock of the backward thrust link 23 under influence of return spring 27 as the key lever 12 is being depressed from radius B to radius D. This tension lock of the backward thrust link 23 is also described as contractive tension lock or thrust meaning that while the key lever is being depressed, the energy required to respond the type bar 6 effects contractive pressure or backward thrust from pivot 26 to pivot 24 instead of expansive tension, or pull. The contractive tension of the backward thrust link 23 stops its oscillation and the link is moved bodily downward with the key lever, as shown in 35 Fig. II as the vibratory lever 18 throws the upper end of divert tension line J J upward until pivot 26 crosses the divert tension line J J into the zone of reaction L. Simultaneously with contractive tension lock of the 40 backward thrust link 23, backward draw link 22 operates under expansive tension between pivots 24 and 25 while the key lever 12 is being depressed from radius B to radius D to respond the type bar 6 from radius E to printing point A, and the expansive tension of the 45 backward draw link 22 being relaxed while the key lever continues the incident of depression from radius D to radius C and simultaneously with the recoil of the type bar 6 from 50 the printing point A back to radius of rest E.

A change in correlative position of pivots 24 and 25 in the actuating plane bring pivot 26 within the lower zone of reaction L thereby releasing the contractive tension lock of 55 the backward thrust link 23. The release of contractive tension lock of the backward thrust link 23 permits it to resume oscillation about the time the type impacts the printing point A. When link 23 resumes oscillation, 60 there being no further obstruction to the recoil of the type 6, it immediately recoils from A to E while the key lever 12 continues its incident of depression from D to C and contacting with bar 15°. The tri-pivotal relationship of pivots 24 and 25 and 26 is neces-

sary to effect the essential means of breaking reversely said coupling after printing impact of the type bar for returning of said type bar to normal position while the key lever is held depressed.

The dotted line M M from pivot 24 and 25 indicates the relative relationship of the tri-pivots of the coupling. Dotted line M M, Fig. I shows where the tri-pivotal relationship forms obtuse angle at pivot 26 pointing upward during normal position and effecting response of the type bar during depression of key lever. Dotted line M M, Fig. II shows the alignment of tri-pivotal relationship at the time the type bar completes its response 75 and begins to recoil. Dotted line M M, Fig. III shows the vertex of obtuse angle at pivot 26 formed by the tri-pivotal relationship pointed downward as the type bar recoils.

29 is a return bar extending across the machine above the rear end of backward draw link communicating therewith restoring said coupling to normal operative position when the key lever is released.

30 is a trip rod extending across the writing machine comprising a core 30a with noise absorbing insulation. Upon depression of key lever 12 the front end of the backward draw link 22 moves upward causing the upward edge near the front end of said draw link to 85 communicate with the lower part of trip rod 20 providing additional means of breaking reversely said coupling.

It should be understood that the present improvement is capable of a large range of 100 modification within the scope of the invention, and variations may be resorted to within the scope of the invention, and portions of the improvement may be used without others.

What I claim as new and desire to secure 105 by Letters Patent, is:

1. In a typewriting machine, a type bar, an angular vibratory lever pivoted at its lower end, a backward pull link operatively connecting the vibratory lever and type bar, 110 a key lever pivoted at its rear end, a reversely breaking actuating coupling rearwardly disposed in a plane above the key lever operatively connecting the vibratory lever and key lever for moving the type bar to printing point upon depression of the key, means reversely breaking said coupling after the printing impact to return the type bar to normal position while the key lever is in depressed position, means restoring said coupling to 120 normal operative position upon release of the key lever.

2. In a type key action, a type bar, an angular vibratory lever pivoted at its lower end, a backward pull link operatively connecting 125 the vibratory lever and type bar, a key lever pivoted at its rear end, a reversely breaking actuating coupling with the elements thereof in folding relation operatively connecting the key lever and vibratory lever, the elements 130

- of said coupling moving the type bar to printing point upon depression of the key lever, means unfolding said elements reversely breaking said coupling after the printing impact of the type bar, means restoring the unfolded elements of said coupling to normal operative foldment upon the release of the key lever.
3. In a typewriting machine, a type bar, 10 an angular vibratory lever with rearward and forward vertices of its angled—ends thereof disposed vertically and pivoted at its lower end—its upper end vibrating backwardly—part between said vertices being horizontal— 15 part below rear vertex being perpendicular to the key lever—part above the forward vertex slanting backwards, a backward pull link operatively connecting the vibratory lever and type bar, a key lever pivoted at its rear end, 20 a reversely breaking actuating coupling operatively connecting the key lever and vibratory lever moving the type bar to the printing point upon depression of the key lever, means reversely breaking said coupling after printing 25 impact of the type bar for returning the type bar to normal position while the key lever is in depressed position, means restoring said coupling to normal operative position upon release of the key lever.
4. In a type key mechanism and action, a type bar, an angular vibratory lever pivoted at its lower end, a pivot bar extending across the machine for pivoting the lower end of the vibratory lever, a backward pull link operatively connecting the vibratory lever and type bar, a key lever pivoted at its rear end, a downward offset formed intermediately the 35 ends of said key lever providing room for the pivot bar of said vibratory lever, a reversely 40 breaking actuating coupling operatively connecting the key lever and vibratory lever to move the type bar to the printing point upon the depression of the key lever, means reversely breaking said coupling after the printing 45 impact of the type bar for returning the type bar to normal position while key lever is in depressed position, means restoring said connection to normal operative position upon release of the key lever.
5. In a type-key action, a type bar, an angular vibratory lever pivoted at its lower end, a backward pull link operatively connecting the vibratory lever and type bar, a key lever pivoted at its rear end, a reversely breaking 55 actuating coupling operatively connecting the key lever and vibratory lever comprising a backward thrust link and a backward draw link pivoted intermediately of its ends to the forward vertex of the vibratory lever and 60 connecting the vibratory lever and backward thrust link for moving the type bar to the printing point upon depression of the key lever, means reversely breaking said coupling after printing impact of the type bar, means 65 returning the type bar to normal position

while key lever is in depressed position, means restoring said coupling to normal operative position upon release of the key lever.

6. In a typewriting machine, a type bar, 70 an angular vibratory lever pivoted at its lower end, a backward pull link operatively connecting the vibratory lever and type bar, a key lever pivoted at its rear end, a reversely breaking actuating coupling operatively connecting the vibratory lever and key lever 75 comprising a backward draw link and a backward thrust link connecting the key lever and draw link providing a backward thrust upon the latter for moving the type bar to printing point upon depression of the key lever, means reversely breaking said coupling after printing impact of the type bar for returning the type bar to normal position while the key lever is in depressed position, means restoring said coupling to normal operative position upon release of the key lever.

7. In a typewriting machine key, a type bar, an angular vibratory lever pivoted at its lower end, a backward pull link operatively connecting the vibratory lever and type bar, a key lever pivoted at its rear end, a reversely breaking actuating coupling operatively connecting the vibratory lever and key lever comprising a backward thrust link and a backward draw link relatively long and short 95 in length moving the type bar to printing point upon depression of the key lever, means reversely breaking said coupling after printing impact of the type bar for returning the type bar to normal position while key lever is in depressed position, means restoring said coupling to normal operative position upon release of the key lever.

8. In a type key action and mechanism, a type bar, an angular vibratory lever pivoted at its lower end, a backward pull link operatively connecting the vibratory lever and type bar, a key lever pivoted at its rear end, a reversely breaking actuating coupling operatively connecting the key lever and vibratory lever comprising a backward draw link angular formed and the vertex of said angle pointing upward, an upwardly projecting arm provided by said key lever operating in the lower angular plane of said backward draw link, a backward thrust link—the front end thereof pivoted to said upwardly projecting arm and rear end pivoted to the rear end of said draw link moving the type bar to the printing point upon depression of the key lever, means reversely breaking said coupling after printing impact of the type bar returning the latter to normal position while key lever is in depressed position, means restoring said coupling to normal operative position upon release of the key lever.

9. In a type-key action and mechanism, a type bar, an angular vibratory lever pivoted at its lower end, a backward pull link operatively connecting the vibratory lever and type

bar, a key lever, a saddle-backed seat provided by said key lever, a reversely breaking actuating coupling operatively connecting the key lever comprising a backward thrust link and a backward draw link moving the type bar to printing point upon depression of the key lever, a fulcrum trip nose provided by the rear end of said backward draw link extending rearwardly and communicating with the saddle-backed seat reversely breaking said coupling after printing impact of the type bar for returning the latter to normal position while the key lever is in depressed position, means restoring said fulcrum trip nose to normal operative position on the saddle-backed seat upon release of the key lever.

10. In a mechanism and action for a type-key, a type bar, an angular vibratory lever pivoted at its lower end, a backward pull link operatively connecting the vibratory lever and type bar, a key lever pivoted at its rear end, a reversely breaking actuating coupling operatively connecting the key lever and vibratory lever comprising a backward draw link and a backward thrust link moving the type bar to printing point upon depression of the key lever, means reversely breaking said coupling after the printing impact of the type bar, a return spring disposed above the key lever and its rear end supported by the forward end of the backward draw link and a cross bar in front of the machine supporting the forward end of said return spring returning the type bar to normal position while key lever is in depressed position, means restoring said mechanism to normal operative position upon release of the key lever.

40 11. In a key action for a typewriting machine, a type bar, an angular vibratory lever pivoted at its lower end, a backward pull link operatively connecting the vibratory lever and type bar, a key lever pivoted at its rear end, a reversely breaking actuating coupling operatively connecting the key lever and vibratory lever moving the type bar to printing point upon depression of the key lever, means reversely breaking said coupling after the printing impact of the type bar to return the type bar to normal position while key lever is in depressed position, a pull spring in the rear of the machine above the key lever actuating the latter to its normal elevated position restoring said coupling to normal operative position upon release of the key lever.

12. In a typewriting machine, a type bar, an angular vibratory lever pivoted at its lower end, a backward pull link operatively connecting the vibratory lever and type bar, a key lever pivoted at its rear end, a reversely breaking actuating coupling operatively connecting the key lever and vibratory lever comprising a backward draw link and a backward thrust link moving the type bar to

printing point upon depression of the key lever, means reversely breaking said coupling after printing impact of the type bar returning the type bar to normal position while key lever is in depressed position, a return bar extending across the machine in the rear of said vibratory lever cooperating with the backward draw link restoring said coupling to normal operative position upon release of the key lever.

13. In a type-key action and mechanism, a type bar, an angular vibratory lever pivoted at its lower end, a backward pull link operatively connecting the vibratory lever and type bar, a key lever, a reversely breaking actuating coupling operatively connecting the key lever vibratory lever comprising a backward thrust link and a backward draw link moving the type bar to printing point upon depression of the key lever, means reversely breaking said coupling after the printing impact of the type bar for returning the type bar to normal position while the key lever is in depressed position, a noise absorbing contact point provided by the key lever intermediately of its ends communicating with the under-edge of the front end of said draw link restoring said coupling to normal operative position upon release of the key lever.

14. In a type-key action and mechanism, a type bar, an angular vibratory lever pivoted at its lower end, a backward pull link operatively connecting the vibratory lever and type bar, a key lever pivoted at its rear end, a reversely breaking actuating coupling operatively connecting the key lever and vibratory lever comprising a backward draw link and a backward thrust link moving the type bar to printing point upon depression of key lever, a trip rod extending across the machine in front of the vibratory lever above the forward end of the backward draw link—said trip rod comprising a core with noise absorbing insulation the lower surface thereof communicating with front end of said draw link reversely breaking said coupling after the printing impact of the type bar for returning the latter to normal position while key lever is in depressed position, said cushion rod communicating with the vibratory lever to effect smooth and quiet operation of the latter and determine its normal position after operation.

15. In a type-key action and mechanism, a type bar, an angular vibratory lever pivoted at its lower end, a backward pull link operatively connecting the vibratory lever and type bar, a key lever pivoted at its rear end, a reversely breaking actuating coupling operatively connecting the key lever and vibratory lever comprising a backward draw link and a backward thrust link, a forward border pivot connecting the vibratory lever and draw link intermediately of their respective

ends, a backward border pivot connecting the draw link and thrust link, an interior pivot connecting the thrust link and key lever above a line drawn through the border pivots for moving the type bar to printing point upon depression of the key lever, means actuating the interior pivot downward across a divert tension line between the forward border pivot and the backward border pivot reverse-
ly breaking said coupling after printing im-

pact of the type bar for returning the type bar to normal position while the key lever is in depressed position, means restoring said coupling to normal operative position upon release of the key lever.

15

Signed at Fort Collins, in the county of Larimer and State of Colorado, this 4th day of April, A. D. 1927.
